UNITED STATES PATENT OFFICE.

JOHN LEWIS MILTON, OF LOUISVILLE, KENTUCKY.

ELECTRIC IGNITION SYSTEM FOR INTERNAL-COMBUSTION ENGINES.

1,039,171.

Specification of Letters Patent. Patented Sept. 24, 1912.

Application filed October 20, 1911. Serial No. 655,746.

To all whom it may concern:

Be it known that I, JOHN LEWIS MILTON, a citizen of the United States, residing at Louisville, in the county of Jefferson and State of Kentucky, have invented a certain new and Improved Electric Ignition System for Internal-Combustion Engines, of which the following is a full, clear, concise, and exact description, reference being had to the accompanying drawings, forming a part of this specification.

My invention relates to ignition systems for internal combustion engines, and its object is to provide a spark arrester which operates in reverse manner to a distributor. This is used to short circuit high tension current outside of the engine's spark plugs, progressively in the order of firing.

A further object is to admit of starting an automobile engine from the seat without cranking, when the cylinders are full of combustible gas, by simply closing an auxiliary battery switch, in an ignition system in which sparks are normally simultaneously created in two cylinders.

An instance of my invention is illustrated in the accompanying drawing, which is a diagrammatic representation of the circuit.

Referring to the circuit, it will be seen that the current is supplied by means of a generator, G, also a battery, B. One terminal (G³) of the generator winding is connected to the binding post, Z, of timer, T, which is, in turn, connected to both primary windings of the two transformer or induction coils, T¹⁰ and T¹¹, through contacts K¹ and K² of knife switch K. The other generator terminal, G⁴, through conductor, G¹, is joined with one terminal, B¹, of the battery; together these are led to the binding post, Y, of the timer, which is also permanently connected with the condenser, C, through conductor, C¹. Binding post, Y, is also connected to the timer blade, T¹, which is insulated from the ground and cam, T². I have used the timer device disclosed in my U. S. application 443,608, for this circuit. The other pole of the battery is connected to the contact, K⁶, of the knife switch.

The insulated contact, T⁵, of the timer, is connected to contact K⁶ of the knife switch; also to insulated contact T⁶ of the swinging arm, T⁴, which is brought into contact and held in contact while the timer is operating, first with contact T⁷, then with

contact T⁸, by means of the eccentric T³, which is carried by the timer shaft. This arm, T⁴, is pivoted on shaft T⁹. When contacts T⁶ and T⁷ are together the electrical impulse is directed through binding post X, and conductor X¹, to the primary winding, T¹². When contacts T⁶ and T⁸ are together, the electrical impulse is directed through binding post X² and conductor X² to the primary winding T¹¹ of transformer coil, T¹.

When the knife switch is in the position shown in diagram, one terminal of condenser C is connected through conductor C², contacts K⁴ and K², conductor C⁴, contacts K³, K¹ and conductor C³. This places both ends of the condenser across the generating winding of G, and is a similar circuit used in my U. S. applications No. 384,049 and No. 443,608. When the knife switch is thrown to the other side, the generator is thrown out of the circuit and the battery current is then sent to the induction coils through conductors B² and T¹⁴ from one pole, and received through conductor B¹ and the other part of the circuit, as described. The condenser is then placed across the contact points T¹ and T⁵. The auxiliary switch, F, is connected to binding post, Y, and contact, T⁵, so that when the engine is stationary, the battery circuit may be closed and opened for generating and sending a spark to the spark plug.

The interrupter, or timer, includes a cam, T², having wings, as shown, this cam being mounted upon the end of the generator spindle, not shown, and rotating, therefore, at the same speed as the rotor of the generator, and with fixed angularity with respect thereto. The function of the cam is ultimately to cause the appropriate vibration of the contact spring, T¹. This contact spring is mounted upon a metallic pedestal, which, in turn, is attached to the supporting timer plate, and insulated.

When operating on current supplied from the magneto, the contact spring, T¹, is brought into electrical connection with the upper contact of T⁵, before the peak of the wave of electromotive force set up in the generator coil is reached. At or about the instant the peak of the wave is reached, the contact spring is moved suddenly from the upper contact to the lower one of T⁵. This momentarily interrupts the generator circuit, and again closes it almost instantly.

The instant the circuit has been opened

between upper contact of T^5 and spring T^1 , the condenser is charged. This charge continues until the connection is established between the contact of spring T^1 , and lower contact of T^5 , whereupon the condenser is discharged through the primary winding of the transformer, aided, under certain conditions, by the electromotive force of the generator, forces a sudden impulse of current through the primary winding of the transformer. Since the primary winding has been subjected to a diminishing current, and consequently the cores of the transformer to a weakened energization, a very sudden change is caused by the sudden rush of current through the primary winding. This rapid change causes a current impulse of very high tension to be set up in the secondary winding of transformer. It is this high tension current which causes a spark to pass between the electrodes of the spark plug. When the timer is operating on current supplied from the battery, the electrical action is similar, however, there is a continuous, constant pressure current in place of alternating waves.

The high tension circuit consists of two secondary windings, T^{15} and T^{16} , the terminals of T^{15} being connected to spark plugs 1 and 4, and the terminals of T^{16} being connected to spark plugs 2 and 3, also conductors 1-2, 2-2, 3-2 and 4-2, connected respectively to insulated contacts 1^a, 2^a, 3^a and 4^a of SA, which is a spark arrester designed to provide, at predetermined intervals, a path of lower electrical resistance for the electric current than across a spark plug or spark gap in a cylinder, as the conducting arm, S, which is connected to the ground, is rotated. This arm is rotated by the engine at a definite ratio to the timer. For conditions as shown in the diagrammatic drawing, the spark arrester arm will rotate at half engine speed while the timer mechanism operates at engine speed. As the spark arrester arm is rotated it is brought into contact with the insulated contacts in the order in which the engine cylinders are fired. In the diagram the order is shown as 1-2-4-3.

As the timer mechanism operates, a high tension current is created alternately in the secondary windings, T^{16} and T^{15} . When the current is created in T^{16} , it flows through conductor 2-1, across spark plug 2 to the ground. If the spark arrester was not incorporated in the system, the current would flow through the ground, then across spark plug 3, returning by conductor 3-1 to the secondary winding T^{16} . In a standard four cylinder, four cycle internal combustion engine, the current leaping across plug 2 would ignite the gas, and the current would pass across plug 3 just about the time the intake valve of the cylinder in which it is

placed would be opening, the fresh gas, if any, would be too weak or thin to ignite, and successful operation of the engine would result. However, if the engine is stopped, say with cylinder 2 full of gas and in position for starting on the spark when it is desired to start on the spark, and the auxiliary switch F is pressed and released to send the battery current to transformer T^{16} , a spark would occur at plugs 2 and 3. The cylinder in which 3 is placed would be approximately half full of gas, supposing the crank to have stopped, normally at a point 90 degrees from the engine dead center. This spark at plug 3, under some conditions, will ignite the gas at the same time that the gas in the cylinder in which plug 2 is placed is ignited, thereby causing two explosions, then the motor will not start. To overcome this condition I have interposed a spark arrester which, in the condition thus described, would cause the current to pass outside of plug 3, thereby preventing a spark at this plug, and allowing the engine to start rotating by the explosion caused by the spark from plug 2. The same condition will occur for corresponding cycles in the engine.

Many variations of the application of this principle may be suggested, consequently I do not limit myself to the form disclosed in the above specification and the diagrammatic drawing.

What I claim as new and desire to secure by Letters Patent, is:

1. In a multiple cylinder ignition system for internal combustion engines, spark plugs associated with the several cylinders, a source of current, a primary circuit including said source, and an interrupter, a transformer, means for distributing secondary current to the fixed spark gaps in the various cylinders, in combination with means for periodically connecting to the ground the insulated terminal of the spark plug of a cylinder not to be fired as a spark is created in one of the other cylinders.

2. In a multiple cylinder ignition system for internal combustion engines, a primary circuit including a source of current, and an interrupter including said source and a secondary circuit associated with said primary circuit and including a spark arresting device operated by the engine, and which is periodically electrically connected to each of the spark plugs in the order of firing.

3. In a multiple cylinder internal combustion engine, a spark plug associated with each cylinder, a jump spark ignition system for same, consisting of a primary circuit including a source of current and an interrupter, a secondary circuit associated with said primary circuit, means for distributing said secondary current, to the fixed spark gaps in the various cylinders, and a spark

arresting device operated by the engine and which is electrically connected to each one of the spark plugs, thereby establishing a temporary short circuit to the ground in the order of firing, and following the cylinder to be fired during the short-circuiting period.

4. In combination with a multiple cylinder internal combustion engine, spark plugs associated with the several cylinders, a multiple cylinder jump spark ignition system, in which a spark arresting device operated by the engine is electrically connected to all the spark plugs and means for temporarily establishing a low resistance circuit to the ground circuit for each plug through said spark arresting device, in the order of firing, and one engine cycle before said plug is to receive a wave of electric current for igniting the combustible gas.
5. In combination with a multiple cylinder internal combustion engine, spark plugs associated with the several cylinders, a multiple cylinder jump spark ignition system, in which a spark arresting device operated by the engine is electrically connected to all the spark plugs, and which temporarily establishes a low resistance circuit from the high tension circuits leading to each plug to the ground circuit, through said spark arresting device, in the order of firing during the intake cycle of the cylinder in which a

given plug is being temporarily short circuited, and simultaneously with the ignition of the gas in one of the other cylinders.

6. In a multiple cylinder ignition system for internal combustion engines, a primary circuit including a source of current and an interrupter, a secondary circuit associated with said primary circuit and including means for temporarily individually and periodically establishing for each spark plug a circuit of less resistance for the high tension current, than offered by the spark plugs, including the gaps in the cylinders.

7. In a multiple cylinder internal combustion engine, spark plugs associated with the several cylinders, a jump spark ignition system for same, a source of current, a primary circuit including said source and an interrupter, a transformer, means for distributing secondary current to the fixed spark gaps in the various cylinders, in combination with means for causing electric current to return to the transformer windings through a path of lower resistance than across the fixed spark gaps in the cylinders, synchronously with the ignition of gas in one of the cylinders.
